UNITED STATES PATENT OFFICE.

JAMES E. BEAN, OF FOND DU LAC, WISCONSIN, ASSIGNOR TO THE UNITED STATES MANUFACTURING COMPANY, OF SAME PLACE.

CYCLOMETER.

SPECIFICATION forming part of Letters Patent No. 632,332, dated September 5, 1899.

Application filed January 25, 1898. Serial No. 667,846. (No model.)

To all whom it may concern:

Be it known that I, JAMES E. BEAN, of Fond du Lac, in the county of Fond du Lac and State of Wisconsin, have invented a new and Improved Cyclometer, of which the following is a full, clear, and exact description.

The invention relates to cyclometers for use on bicycles and other vehicles; and its object is to provide a new and improved cyclometer arranged to indicate simultaneously the number of miles traveled during the season and the number of miles of the individual trip made at the time.

The invention consists of novel features, parts, and combinations of the same, as hereinafter more fully described, and pointed out in the claims.

Reference is to be had to the accompanying drawings, forming a part of this specification, in which similar characters of reference indicate corresponding parts in all the figures.

Figure 1 is a cross-sectional elevation of the improvement. Fig. 2 is a sectional side elevation of the same on the line 2 2 of Fig. 25 1. Fig. 3 is a sectional plan view of the casing, showing the transmitting-gearing. Fig. 4 is a sectional side elevation of the trip-register. Fig. 5 is an edge view of the units-wheel for the total register and adjacent parts. Fig. 6 is a face view of the same with parts in section and parts broken out. Fig. 7 is an end elevation of the spring for the fraction numeral-wheel. Fig. 8 is a face view of the pawl-and-ratchet mechanism for 30 the fraction-wheel. Fig. 9 is a side elevation of the setting-arm; and Fig. 10 is a detail perspective view of the mechanism for operating the numeral-wheels, parts being broken away.

40 The improved cyclometer is provided with a casing A, preferably made cylindrical in form and provided at its lower end with a dovetailed boss A', on which is adjustably secured a bracket B, adapted to be clamped or otherwise fastened to the axle of the steering-wheel when the device is applied to a bicycle.

On the casing A, adjacent to the boss A', is formed a bearing A², in which is journaled a 50 vertically-disposed shaft C', carrying at its outer end a star-wheel C, adapted to be en-

gaged by a friction-roller D, journaled on a shaft D', carried by a clamp D², adapted to be fastened on one of the spokes E of the steering-wheel, so that the latter at every 55 revolution brings the friction-roller D in mesh with the star-wheel to impart an intermittent rotary motion to the same and to the shaft C'. In order to prevent the wheel C from being carried too far by the friction-roller D, I provide a friction-cap C², fitted to slide loosely on the bearing A² and pressed outward by a spring C³ to hold the outer end of the said cap in frictional contact with the inner side of the star-wheel C. A lug C⁵ in 60 the friction-cap C² fits in a groove in the bearing A² and prevents the cap from turning around and wearing out the spring.

On the inner end of the shaft C' is secured a pinion C⁴ in mesh with a gear-wheel F, 70 mounted to rotate on a stud F', secured to the casing A, and on the upper face of the said gear-wheel F is formed a worm F² in mesh with a pinion G, secured on the shaft G', journaled in suitable bearings within the cas- 75 ing A. On the shaft G' is secured a second pinion G², and the pinions G and G² are at all times in mesh with gear-wheels H and I, of which the latter forms part of the mechanism 80 for actuating the trip numeral-wheels J, J', and J², and the gear-wheel H forms part of the mechanism for actuating the numeral-wheels K, K', K², and K³ for registering the number of miles made during the season. The numerals on the peripheries of said 85 wheels J, J', and J² and those on the peripheries of the other set of numeral-wheels K, K', K², and K³ are visible to the rider of the cycle through a transparent or translucent strip A³, fitted in an opening formed in the 90 peripheral surface of the casing A, as is plainly indicated in Figs. 1 and 2. The sets of numeral-wheels J J' J² and K, K', K², and K³ are arranged one alongside of the other, so that the rider is enabled to see at a glance 95 the number of miles made during a trip, and also the total number of miles made so far in the season. The numeral-wheel J is a fraction-wheel, the wheel J' is the units-wheel, and the wheel J² is the tens-wheel for the 100 trip-registering device. The wheel K is the units-wheel, the wheel K' is the tens-wheel,

the wheel K^2 is the hundreds-wheel, and the wheel K^3 the thousands-wheel for the total-register. Each of the wheels, however, bears the numerals from "0" to "9."

- 5 The trip-registering device is arranged as follows: The gear-wheel I is connected by a pawl-and-ratchet mechanism L with the hub J^3 of the fraction-wheel J, the said hub being mounted to turn loosely on a bearing N, having a polygonal aperture fitted on the correspondingly-shaped outer face of a sleeve A^6 , forming part of the cap A^4 , closing one end of the casing A, the other end being closed by a cap A^5 . The sleeve A^6 is mounted to turn loosely on the enlarged end O of a shaft having its reduced end O' extending in a sleeve A^7 attached to the other cap A^5 . On the inside of the rim of the fraction-wheel J is secured a spring-pawl P, the free end P' of which rests on the peripheral surface of a toothed disk Q, secured on the polygonal sleeve A^6 , the said wheel having the same number of teeth as there are numerals on the numeral-wheels, and the said disk is also provided at one portion of its periphery with a recess Q', so that when the free end of the spring P drops into this recess it comes in contact, by means of a sidewise-projecting tongue P^2 , with a tooth of a toothed wheel J^4 , formed or secured on the web of the units-wheel J', so that the further rotation of the fraction-wheel J rotates the units-wheel J' to bring the next numeral to view under the strip A^3 , and when this takes place the free end of the spring P' travels up the next following tooth on the disk Q, so as to raise the tongue P^2 out of engagement with the corresponding tooth of the wheel J^4 , so as to free the wheel J^4 and allow it to turn. The spring P has its lower end P^3 curved inward to form a dog for the disk Q to prevent accidental return movement of the disk. Now it is evident that the gear-wheel I moves along the fraction-wheel J, and the latter when completing a revolution moves the units-wheel J' such a distance as to bring the next numeral under the strip A^3 , and when the wheel J' completes a revolution it carries the tens-wheel J^2 along by means of a similar spring P and a disk Q^2 , the said tens-wheel being provided with a toothed wheel J^5 , similar to the wheel J^4 . The tens-wheel J^2 is provided with a spring P, engaging a disk Q^3 without a recess Q', the said spring and disk serving to prevent the wheel J^2 from being carried too far by the wheel J', as previously explained. The gearing from the star-wheel C to the gear-wheel I is so proportioned that when the wheel I has made one complete revolution the bicycle has traveled one full mile and the units-wheel is shifted accordingly. When the units-wheel moves from "9" to "0," it shifts the tens-wheel to the next following numeral, as is well known. On the peripheral surfaces of the units and tens wheels J' and J^2 are secured stop-pins J^6 , extending outward from the rims of the

said wheels, and said stop-pins are adapted to abut against the upper edge of the spring-arm R, secured to the inside of the casing. The cap A^4 is provided with an arm A^7 , adapted to be taken hold of by the operator to turn the said cap on the sleeve A^6 when it is desired to move the several wheels J, J', and J^2 back to "0" when starting on a new trip, and it also serves to hold the spring-arm in place while in use, and for that purpose has a depression on its inner side to fit over a small projection near the corner of the case. (See Fig. 9.) Now it is evident that when the operator turns the handle or arm A^7 from the left to the right in the direction of the arrow a' in Fig. 2 then the several wheels J, J', and J^2 will turn with the cap and its integral sleeve A^6 , owing to the pawl-and-ratchet connection between the wheel I and the hub N and the connection of the springs P with the fixed disks Q, Q^2 , and Q^3 . Now as soon as the numeral "0" of the wheel J appears under the strip A^3 the operator turns the handle A^7 in the inverse direction of the arrow a' until the stop-pins J^6 move in engagement with the arm R, so as to prevent further rotation of the units and tens wheels. The trip-register is now set at "0."

The total-amount register has its gear-wheel H mounted to rotate loosely on a bearing N^3 , secured to the polygonal external surface of the sleeve A^7 , and on this gear-wheel is secured a spring S, having its free end in peripheral contact with a disk T, formed in part of its surface with a recess T'. Adjacent to the disk T is arranged the toothed wheel K' , formed or secured on the web of the units-wheel K, so that when the spring S drops at its free end into the said recess T' of the disk T it moves in contact with one of the teeth of the wheel K^4 , so that the further rotation of the gear-wheel H causes the spring to carry the toothed wheel K^4 along with it, and consequently the units-wheel K, so as to bring its numeral to the next position under the strip A^3 . When this takes place, the free end of the spring travels up the peripheral surface of the disk T and out of mesh with the corresponding tooth of the wheel K^4 . The units-wheel K is mounted to turn on a bearing N^4 , held on the sleeve A^7 , and it is provided with a spring P^4 , similar to the spring P and engaging a disk Q^4 , similar to the disks Q, Q^2 , and Q^3 , and the said spring is adapted to engage a toothed wheel Q^4 on the tens-wheel K^2 , which in turn is similarly constructed to the wheel K, so as to actuate at every revolution the hundreds-wheel K^2 , which in turn actuates by a similar mechanism the thousands-wheel K^3 . Now it is understood that during every revolution of the wheel H the units-wheel K is shifted the same as the units-wheel J', owing to the intermediate mechanism between the wheel H and the units-wheel K, the said mechanism taking the place of the fraction-wheel J of the trip-registering device. Thus the rotary motion of

the shaft G' is transmitted simultaneously to the gear-wheels H and I, of which the latter actuates the fraction-wheel J and the former, the gear-wheel H, actuates the units-wheel 5 K, as above described.

Having thus described my invention, I claim as new and desire to secure by Letters Patent—

1. In a cyclometer, the combination with 10 two sets of numeral-wheels, of a gear-wheel for each set of numeral-wheels, a pawl-and-ratchet mechanism for operating the first wheel of each set of numeral-wheels from the gear-wheel, two gear-wheels mounted upon 15 the same shaft and meshing with the first-named gear-wheels, and means for operating the shaft of said gear-wheels from a moving part of a vehicle, substantially as described.
2. In a cyclometer, the combination with 20 two sets of numeral-wheels, of a gear-wheel for each set of numeral-wheels, a pawl-and-ratchet mechanism for operating the first wheel of each set of numeral-wheels from the gear-wheel, two gear-wheels mounted upon 25 the same shaft and meshing with the first-named gear-wheels, a gear-wheel adapted to be driven from a moving part of a vehicle, and a worm formed on the gear-wheel and with which one of the two gear-wheels mesh, 30 substantially as described.
3. In a cyclometer, the combination with independent sets of numeral-wheels, of a star-wheel adapted to be intermittently rotated from a moving part of the vehicle, a shaft carrying 35 two pinions, each geared with a set of numeral-wheels, a worm engaging one of the gear-wheels of said shaft, and gearing between the worm-wheel and the star-wheel, substantially as described.
4. A cyclometer provided with an intermittently-rotating wheel carrying a spring-pawl, a disk normally fixed and having a recess in 40 its peripheral surface for engagement by the

said pawl, and a numeral-wheel mounted to turn and carrying a tooth adapted to register 45 with the said recess to be engaged by the said pawl for intermittently turning the numeral-wheel, substantially as shown and described.

5. A cyclometer provided with a numeral-wheel mounted to rotate loosely and formed 50 with a tooth, a pawl carried by said wheel and adapted to engage the teeth of the adjacent numeral-wheel, and a normally-fixed disk having spaced peripheral teeth and a recess for engagement by the said pawl to hold its 55 wheel against accidental movement and to engage the pawl with a corresponding tooth of the numeral-wheel at the time the pawl extends into the recess, substantially as shown and described. 60

6. In a cyclometer, the combination of a casing having a cap provided with an inwardly-projecting sleeve mounted to turn, numeral-wheels in the casing and connected with the sleeve to turn therewith, peripheral stops on 65 sundry of the numeral-wheels, and a fixed spring-arm on the inside of the casing and with which the stops of the wheels are adapted to engage, substantially as described.

7. In a cyclometer, the combination with 70 an intermittently-rotating wheel, a disk normally stationary and having a recess in its periphery, a numeral-wheel adjacent to the disk and provided with a toothed wheel, and a spring-pawl secured to the inner surface of 75 the rim of the intermittently-rotating wheel, said pawl being adapted to enter the recess of the said disk and provided with a tongue for engaging the toothed wheel of the numeral-wheel when the pawl enters the recess of the 80 disk, substantially as described.
